MOBILE SHIP-TO-PIER GANGWAY
STRUCTURE

Max J. Luther, Jr., Corpus Christi, Tex.

Application September 23, 1949, Serial No. 117,380

5 Claims. (Cl. 114—0.5)

1

My invention relates to improvements in mobile ship-to-pier gangway structures for ships of the oil tanker type, and the like.

By way of premise, oil tankers are constructed with an elevated catwalk on the deck running for a substantial distance along the longitudinal center of the ship.

The primary object of my invention is to provide for such ships practical gangway structure extending from the catwalk over the sides of the ship to a pier, and which is adapted to be moved along the ship into different set positions to locate the structure relative to the pier, as may be required by mooring of the ship in different positions alongside the pier, or for other reasons.

Another object is to provide a gangway structure of the type and for the purpose above set forth which is safe, easy to operate, economical to manufacture, and adapted to be installed on present-day tankers without any change in the basic structure of the tanker.

Other and subordinate objects, within the purview of my invention, together with the precise nature of my improvements, will be readily understood when the succeeding description and claims are read with reference to the drawings accompanying and forming part of this specification.

In said drawings:

Figure 1 is a fragmentary view in plan illustrating an oil tanker ship equipped with my improved gangway structure;

Figure 2 is a view in transverse section taken on the line 2—2 of Figure 1;

Figure 3 is a fragmentary view in plan drawn to a larger scale and partly broken away;

Figure 4 is a view in longitudinal section taken on the line 4—4 of Figure 3;

Figure 5 is a view in transverse section taken on the line 5—5 of Figure 3;

Figure 6 is a fragmentary view in transverse section taken on the line 6—6 of Figure 3 and drawn to a larger scale; and

Figure 7 is a fragmentary view in transverse section taken on the line 7—7 of Figure 3 and drawn to a larger scale.

Referring to the drawings by numerals, 1 designates the hull of an oil tanker, or ship, equipped according to my invention and located alongside a pier 2, the illustration of the tanker and pier being conventional as sufficient for the present purposes. The numeral 3 designates the usual longitudinal, central catwalk elevated above the deck 4 by side supports 5 surmounted by channel iron bars 6 extending along opposite sides of the catwalk 3. The usual side rails of such ships, relatively lower than the catwalk 3, are designated 7.

According to my invention, duplicate mobile gangway structures are provided upon opposite sides of the catwalk 3. These structures, desig-

2

nated 8, 9 being duplicates, a description of one will suffice for both.

For example, the mobile gangway structure 9 comprises a bridge section 10 extending from one side of the catwalk 3 to the side rail 7 opposite said side of the catwalk 3. The bridge section 10 comprises an elongated, sheet metal, channeled deck 11 forming upturned, longitudinal guide flanges 12 extending along the same for a purpose presently seen. The inboard end of the deck 11 rests upon the sides laterally along the channel bar 6 at the side of the catwalk 3 from which said bridge section 10 extends.

At the outboard end thereof, the deck 11 is formed with a downwardly and outwardly inclined ramp 13, for a purpose presently seen, and which extends to the side rail 7 over the same and is equipped with an inverted end channel guide 14 beneath the same riding upon a U-shaped track bar 15 suitably fixed to and extending along said rail 7 on the inboard side and adjacent the upper edge thereof. As will, of course, be manifest, the deck 11 between the catwalk 3 and the ramp 13 is supported horizontally, level with the catwalk 3 and parallel with the deck 4, by the channel bar 6 upon which it rests and by the track bar 15. An additional support for the deck 11 is provided and will presently be described.

A pair of opposite ladder sections 16 are suitably fixed to opposite sides of the bridge section 10 adjacent the ramp 13 and which incline downwardly and outwardly thereof with lower ends terminating a short distance above the deck 4.

Hand railings 17 extend along the sides of the deck 11 upon opposite sides of the ladder sections 16 and are suitably fixed in keepers 18 provided on the flanges 12 of said deck.

A rectangular frame 19 upstanding from the deck 4, parallel with the catwalk 3, also supports the deck 11 between the pair of ladder sections 16 and the ramp 13, said frame 19 including end uprights 20 rising from and suitably fixed to the deck 4, a top channel bar 21 upon which the deck 11 rests and is laterally slidably, and diagonal strut bars 22 connected by a gusset plate 23.

Means are provided for propelling the bridge sections 10 laterally along the catwalk 3 on the channel bars 6, 21 and the track section 15 and will now be described. A pair of rack bars 24, 25 extend along the channel bars 6, 21 supporting said bridge sections 10. A crankshaft 26 is suitably journaled in the deck 11 to depend therefrom alongside the rack bar 24 with a gear pinion 27 fast thereon and meshing with said rack bar. A crankshaft 28, like the crankshaft 26, is journaled in bearings 29 on cross-bars 30 connecting the pair of ladder sections 16 and has

fast thereon a gear pinion 31 meshing with the rack bar 25.

A gangplank section 32 is provided for extension endwise out of the bridge section 10 onto the pier 2 and for retraction into said bridge section 10, when not in use.

The gangplank section 32 comprises a sheet metal deck 33 of inverted channel form fitting on the deck 11 of the bridge section 10 between the flanges 12 and provided with supporting side rollers 34 for running on said deck 11, said rollers 34 being arranged in pairs suitably spaced apart longitudinally of the deck 33 and mounted on cross rods, as at 35, suitably secured in the sides of the deck 33. Suitably trussed hand railings 36 of the conventional type extend along the sides of the deck 33 of the gangplank section 32. Corner caster wheels 37 on the outboard end of the deck 33 are provided for riding on the pier 2.

A pair of cams 38 are provided at the lower end of each ladder section 16, at opposite sides of the section, and which are fast on a cross shaft 39 journaled in the sides of said sections 16. A hand lever 40, fast on one end of the cross shaft 39, provides for rocking said shaft to rock the cams 38 into frictional engagement with the deck 4, as shown at the right-hand side of Figure 4, to frictionally lock the gangway structure 9 against lateral movement. In the friction locking position of the pairs of cams 38, the hand levers 40 abut the deck 4 and overbalance the pairs of cams 38 to retain the same in locking position. Movement of the hand levers 40 into an opposite position, as shown at the left-hand side of Figure 4, unlocks the cams 40, as will be readily understood.

The use and operation of the described gangway structure will be readily understood. The gangplank section 32, when not in use, is rolled into the bridge section 10 for support thereon in retracted, inboard position, as illustrated in Figures 3, 4 and 5, and also in Figures 1 and 2 as regards the gangplank section of the gangway structure 8. In the retracted position thereof, the gangplank section 32 may be lashed tight to the bridge section 10 in any suitable manner, not shown. When the tanker, or ship, 1 is suitably moored to the pier 2, the gangway structure 8 may be moved, or adjusted, along the catwalk 3 and side rail 7 into a desired position suitable for lowering the gangplank section 32, and by operation of the hand cranks 26, 28 to cause the gear pinions 27, 31 to roll along the rack bars 24, 21 and thereby move said structure 8 into desired position. Then the bridge section 10 may be frictionally locked in set position by means of the cams 38 and the hand levers 40 in the manner already described.

To lower the gangplank section 32, it is rolled and projected out of the outboard end of the bridge section 10 to the desired extent, with the outboard end thereof riding on the pier 2 and its inboard end resting on the ramp 13. In this connection, the angle at which the gangplank section 32 is disposed, when lowered, may be varied, as occasion may require, by variably positioning its inboard end on the ramp 13. The gangplank section 32 may be lashed to the bridge section 10 in any selected, projected position, or otherwise anchored to said section 10 in any suitable manner.

The foregoing will, it is believed, suffice to impart a clear understanding of my invention, without further explanation.

Manifestly, the invention, as described, is susceptible of modification, without departing from the inventive concept, and right is herein reserved to such modifications as fall within the scope of the appended claims.

Having described the invention, what is claimed as new is:

1. In a ship including a side rail, and a raised catwalk extending longitudinally and centrally of the ship's deck, a gangway structure including a bridge section extending from one side of the catwalk to said rail, means to mount said bridge section on said catwalk and rail for travelling movement along the same, and a gangplank section carried by and on said bridge section and extensible out of the same over said rail.

2. In a ship including a side rail, and a raised catwalk extending longitudinally and centrally of the ship's deck, a gangway structure including

10 a bridge section extending from one side of the catwalk to said rail, means to mount said bridge section on said catwalk and rail for travelling movement along the same, a pair of ladder sections depending from opposite sides of said

25 bridge section with lower ends terminating adjacent said deck, means on said ends of the ladder sections operative into frictional engagement with said deck to hold said bridge section against travelling movement, and a gangplank carried

30 by and on said bridge section and extensible out of the same over said rail.

3. In a ship including a side rail, and a raised catwalk extending longitudinally and centrally of the ship's deck, a gangway structure includ-

35 ing a bridge section extending from one side of the catwalk to said rail; means to mount said bridge section on said catwalk and rail for travelling movement along the same, a gangplank section carried by and on said bridge section and extensible out of the same over said rail,

40 a support for said bridge section rising from said deck intermediate the catwalk and rail and on which said bridge section is laterally slideable in its travelling movement and rack and pinion devices on said bridge section and support de-

45 vices for moving said bridge section.

4. In a ship including a side rail, and a raised catwalk extending longitudinally and centrally of the ship's deck, a gangway structure including

50 a bridge section extending from one side of said catwalk to said rail and having inboard and outboard ends slidably mounted respectively on said catwalk and rail for travelling movement of said bridge section along said catwalk and rail,

55 said bridge section including a downwardly and outwardly inclined ramp leading to said rail, and a gangplank section carried by said bridge section and roller supported thereon for extension out of said bridge section over said rail and lowering on said ramp section.

5. In a ship including a side rail, and a raised catwalk extending longitudinally and centrally of the ship's deck, a gangway structure including

60 a bridge section extending from one side of the catwalk to said rail, means to mount said bridge section on said catwalk and rail for travelling movement along the same, a gangplank section carried by and on said bridge section and ex-

65 tensible out of the same over said rail, and manipulative means under said bridge section

70 operative from the deck to cause travelling movement of said bridge section.

MAX J. LUTHER, JR.
